KNITTING METHOD AND MACHINE

James L. Getaz, New York, N. Y., assignor to
 Scott and Williams, Incorporated, Laconia,
 N. H., a corporation of Massachusetts

Application June 13, 1940, Serial No. 340,292

29 Claims. (Cl. 66—135)

This invention relates to a knitting method and machine and particularly to a knitting method and machine adapted for the production of wrapping in a broad rib fabric.

Broad rib fabrics, for example, of the common 6 x 3 rib type, may be produced on circular knitting machines of the double cylinder type such as illustrated, for example, in Spiers Patent 1,210,866, Bently Patents 1,713,736 and 2,045,938, and Deans Patent 2,101,494. Reference may also be made to the application of Harold E. Houseman, Serial No. 302,443, now Patent 2,237,143, for the illustration of a recent development of this type of machine from which details of a machine embodying the present improvements may be understood.

For the purpose of providing decoration through the leg and perhaps the instep of a stocking, it is customary to effect wrapping of embroidery yarns about selected needles, producing, for example, clock designs or more elaborate designs which may, in some cases, decorate substantially the entire circumference of the stocking. The production of this wrapping requires the imparting of motion to a wrap yarn to cause it to loop about one or more needles which are to knit it into the fabric along with the yarn or yarns forming the circular courses. In the operation of the double cylinder type of machine during the formation of broad ribs, needles are located in both the upper and lower cylinders, those in the lower cylinder forming the broad ribs and those in the upper cylinder the narrow intermediate ribs. There is thus formed across the space between the cylinders, which must be quite limited at best, a cage of needles offering difficulties in the provision of means for effecting proper movements of embroidery yarns. This is not particularly serious in the production of individual needle wrapping, for example, as disclosed in Kent Patent 2,065,469, in which a particular embroidery yarn is caused to wrap only a single needle at any time. The production of panel wrapping, however, in which a single embroidery yarn is knitted into a plurality of wales in the formation of a single course involves substantial difficulties because of the fact that such panel wrapping generally requires a wide swing of the embroidery yarn relative to the needles so that it may be taken by any of a group of selected needles within a particular range. The difficulty is experienced particularly in getting the wrap yarn into position, following the passage of needles in the upper cylinder, to be engaged by needles forming a wide rib panel in

the lower cylinder with properly timed withdrawal to get it out of the way of the next needles in the upper cylinder.

It is the broad object of the present invention to provide a method and means for insuring proper wrapping on as many needles as possible forming a broad rib. It will be understood that the term "wrapping" herein is used in its usual sense of referring to securing engagement of an embroidery yarn in the formation of a single course by needles which may not be adjacent each other and which, in a strict sense, do not have the embroidery yarn wrapped about them, but have it presented to them within their hooks so as to be knit thereby.

The above broad object of the invention, as well as other objects particularly relating to details, will become apparent from the following description, read in conjunction with the accompanying drawings, in which:

Figure 1 is a vertical section taken through a knitting machine embodying the improvements, various parts being omitted from this section for purpose of clarity;

Figure 2 is an elevation, partly in section, showing particularly the embroidery yarn carrying and controlling devices;

Figure 3 is a similar view showing the embroidery yarn assembly in a raised position in which threading can be effected;

Figure 4 is a fragmentary plan view, partially in section, illustrating the controlling means for effecting selection of needles for wrapping;

Figure 5 is a perspective view illustrating controlling means for the mechanism of Figure 4;

Figure 6 is a fragmentary elevation illustrating further controlling devices for the mechanism of Figure 4;

Figure 7 is a fragmentary sectional view showing controlling means for the wrap fingers;

Figure 8 is a fragmentary section taken on the plane indicated at 8—8 in Figure 7;

Figure 9 is a plan view of a verge used in the improved machine;

Figure 10 is a sectional view of the same taken on the plane indicated at 10—10 in Figure 9;

Figure 11 is a side elevation of a wrap finger used in the present machine;

Figure 12 is an elevation showing in end view two associated wrap fingers in the machine;

Figure 13 is a perspective view showing the controlling devices for certain of the cams of the machine;

Figure 14 is a fragmentary perspective view illustrating the controlling elements for an abut-

ment arranged to engage the embroidery yarns during wrapping;

Figure 15 is an inside development showing the slider controlling cams of the machine;

Figure 16 is a diagrammatic view illustrating the fashion in which control of sliders takes place in the production of selective wrapping; and

Figures 17 to 20, inclusive, are perspective views, distorted for clarity of illustration, illustrating the fashion in which the embroidery yarn is handled for the production of selective wrapping on needles of a wide panel.

The machine embodying the present invention comprises lower and upper bed plates 2 and 4, respectively, joined by supporting posts 6. In the lower bed plate 2 there is mounted for rotation a gear 8 secured to, and held in position by, a bevel gear 10 driven by a bevel gear 12 having selective rotary or reciprocatory movements. The devices for imparting motion are illustrated in Fig. 7 of the patent to H. E. Houseman No. 2,180,708, dated November 21, 1939. Gear 144 of this patent corresponds to gear 12 of the present machine. The lower cylinder 14 is secured to the gear 8. During rib knitting this cylinder carries the so-called frame needles which produce the broad ribs extending outward in the finished stocking.

Gear 8 meshes with a pinion 16 carried by a vertical shaft 18, which, at its upper end, supports a pinion 20 driving the upper gear 22 mounted in the bed plate 4 by means of a cover plate 24. Gear 22 supports the upper cylinder 26 and is secured thereto.

Located within the lower end of the upper cylinder is the verge 28, shown particularly in Figures 9 and 10. This verge fits the bore of the upper cylinder and is secured to a shaft 30, having a suitable bearing in the frame of the machine (see Figures 2 and 3). The verge 28 is caused to rotate with the cylinders 14 and 26 by reason of the provision of a key 32 carried by the verge and engaging a slot formed in the inside of the cylinder 26. To secure fine adjustment, this key 32 is located in a slot 33 larger than the key and is held in adjusted position in said slot by means of screws 35 having the under sides of their heads beveled to engage beveled surfaces at the top of the key. Thus accurate angular adjustment of the verge with respect to the cylinder 26 may be effected.

The verge of a machine of this type is provided with a cylindrical wall fitting the inside of the cylinder. In the present instance, however, the verge is cut away as indicated at 34, in the locations at which the embroidery yarn fingers are located, and the cylinder 26 is either cut away at such points or shortened throughout its circumference to permit the wrap yarn fingers to pass outwardly, as indicated, for example, at 37 in Figures 1 and 10. The shortening of the entire cylinder is preferable so that wrapping may take place anywhere rather than only at locations corresponding to the cutaway points.

The verge 28 carries a pin 36 which enters an opening in a wrap finger guide member 38 secured to a sleeve 40 surrounding the verge shaft 30 and splined thereto as indicated at 42. The guide member 38 is slotted as indicated at 44 for the guidance of the wrap fingers 48 and is provided with yarn guides 46 leading the yarns to the eyes 49 of the wrap fingers. Also secured to the sleeve 40 is a wrap finger supporting member 50, which is slotted at 52 to receive the upper ends of the wrap fingers. A circumferential

groove 54 in the member 50 receives a spring band 56 which, by extending across the slots 52 provides a series of fulcrum points for the wrap fingers 48. These wrap fingers are provided with sloping slots 58 to embrace the band 56 as illustrated in Figure 1. The wrap fingers are held in position in the carrier 50 by means of a spring band 60 engaging notches 61 therein and are normally urged into position to withdraw their lower ends inwardly by an additional spring band 65 engaging notches 63 therein.

At their upper ends, the wrap fingers are provided with butts 62, which may be selectively broken away to secure proper patterning action as hereafter described. Generally it is desirable to have the wrap fingers arranged in groups of two or more. When that is the case, though their upper ends may be spaced for convenience in mounting in parallel, suitably spaced grooves, their lower ends should be closely adjacent each other, and for this purpose the wrap finger or fingers which trail the first of the group have their lower ends turned as illustrated at 67, so that these lower ends are closely adjacent each other and, from the standpoint of operation, move in substantially the same radial paths.

The carrier 50 carries yarn guides 64 to lead the yarn from the bobbins 68, carried by a plate 66 secured to the sleeve 40, and the tension devices 72 and take-up devices 74, carried by a second plate 70, also secured to sleeve 40. As illustrated particularly in Figures 2 and 3, the sleeve 40 and the parts carried thereby may be shifted from the operative position of Figure 2, in which the wrap fingers are so located as to present yarns to the needles, to the position illustrated in Figure 3 in which the lower ends of the wrap fingers are located in position for threading. In such sliding movement, the angular position of the elements is substantially retained by the splined connection 42. However, this connection is not depended upon to locate the wrap fingers in position during operation, this being effected by engagement of the member 38 with the pin 36, so that very accurate alignment is secured. A latch 71 may be provided to retain the sleeve 40 and its associated parts in raised position for threading.

Normally, a verge such as 28 will carry a full set of verge bitts 76 about its circumference to effect proper stitch formation by the needles operating in the upper cylinder, said bitts 76 acting as elements to knock over stitches as the needles in the upper cylinder are raised. In the present case, however, most of these verge bitts are omitted, inasmuch as they would interfere with the wrap yarns. If the ribs knitted by the upper cylinder needles are formed on three needles each, it is found sufficient to provide pairs of bitts 76, as indicated in Figures 17 to 20, arranged between the needles of the upper cylinder groups, these bitts being held in slots in the verge 28 by means of a plate 78.

As illustrated most clearly in Figure 17, sliders 80 are located in the lower cylinder and sliders 84 in the upper cylinder, these being arranged to control the movements of needles 82 in conventional fashion. Sinkers 83, of usual type, are arranged in the lower cylinder to cooperate with the needles in the formation of stitches.

The lower sliders 80 carry knitting butts 86 and transfer butts 88 and are also provided with butts 90 of saw tooth shape of which the lowermost 92 may be formed as illustrated. The upper sliders 84 carry knitting butts 94 and transfer

butts 96. Hooks 98 and 100 on the lower and upper sliders respectively are arranged to engage the needle hooks in the usual fashion to control needle movements.

The selective control of the lower sliders to position needles for wrapping is effected through the use of a trick wheel 102, secured to an upright shaft 104. This trick wheel is provided with slots in the usual fashion and contains tricks 106, provided with selectively arranged butts adapted to engage and operate the follower portions 108 of a series of levers 110 normally urged into engagement with the tricks by individual springs 112. Each of the levers 110 is provided with a rounded end 114 engageable in a notch in a cam slide 116. These slides are mounted in a fixed block 118 and are provided with ends 120 engageable selectively with the teeth 90 of the lower sliders. In the present instance, six of these slides are illustrated selectively engageable with the six butts 90 on the lower sliders.

Secured to the shaft 104 is a ratchet wheel 122 operable by reciprocating movements of a pawl 124 longitudinally adjustable on a carrying rod 126 and urged downwardly and to the right, as viewed in Figure 4, by spring 128. Guard surfaces 130 and 132 are formed on a guard member 134 journaled on the shaft 104 and adapted to be moved against the tension of spring 138 by a link 136. Normally during operation this guard member occupies the position illustrated in Figure 4, so that the pawl 124 may engage the teeth and advance the trick wheel. If it is desired to interrupt the operation, the guard 134 is so moved as to bring its surface 130 into engagement with the pawl throughout its stroke to move the pawl outwardly so that it will not engage the teeth 122. When it is desired to time up the trick wheel, for example, during the formation of the toe of a stocking, the lower guard surface 132 is moved adjacent the end of pawl 124, so that, while the pawl 124 will advance the normal teeth of ratchet 122, it will fail to engage a low tooth 140 of the series, so that, despite continued operation, the trick wheel will be brought to rest with this tooth opposite the position of pawl 124.

The guard is controlled through the mechanism illustrated in Figure 5. Link 136 carries a collar adapted to be engaged by the pin 158, through which link 136 extends, carried by one arm of a bell crank 160, the other arm of which is engageable by an arm 162 carried by the hub of a lever 164, which is provided with a follower 166 engageable by cams 168 on the main pattern drum of the machine and also with a follower 170 engageable by lugs 172 on a pattern chain 173. By this arrangement, and as described in greater detail hereafter, the trick wheel may be caused to advance or pause at desired times and may be timed up during the completion of the formation of a stocking.

Figure 6 illustrates the devices for effecting movements of the trick wheel 102. The link 126 is connected to a bell crank 186 pivoted at 184 and having an arm 182 connected by a link 180 to a lever 188 pivoted at 189 to the frame of the machine and movable by cams 194 and 196 carried by gear 192 corresponding to gear 176 illustrated in Houseman Patent 2,180,708, referred to above. The gear 176 makes one revolution for every two courses during rotary knitting. Consequently, if advance of the trick wheel is to occur upon the formation of every course, two cams are provided on gear 192 as illustrated. If advance of the trick

wheel is to be effected, however, only on alternate courses, only one of these cams is provided. Desirably there are as many teeth on ratchet 122 as there are tricks, so that each stroke of pawl 124 will effect the substitution of one trick for another in active position. Thus changes are effected every course or every two courses, depending upon whether there are present on gear 192 one or two cams for operating lever 188.

At its upper end the shaft 104 carries a second trick wheel 178 provided with tricks 174 in slots therein corresponding in angular position with the slots in trick wheel 102. The tricks 174 are also provided with properly arranged butts adapted to engage the follower portions 176 of a series of levers 178, the ends of which are arranged to engage bell cranks 180 pivoted at 182 and urged in clockwise direction as viewed in Figure 7 by individual springs 184 which urge the levers 178 into engagement with the tricks. Movements of bell cranks 180 under the actions of springs 184 are limited by individual adjustable stops 194. Bell cranks 180 are arranged to engage the ends 186 of operating levers 188 pivoted at 189 to the frame and urged in clockwise direction as viewed in Figure 7 by individual springs 190. The ends 186 of these levers are arranged to engage selectively the butts 62 of the wrap fingers 48 to cause the lower ends thereof to swing outwardly across the needle circle. A cam 192 is provided to engage the wrap fingers below their pivots at 56 to return them inwardly at the end of a wrap operation (see Figure 1).

An upright shaft 198 is provided at its upper end with a finger 196 of sufficient vertical extent to be engageable with all of the levers 178. At its lower end this same shaft carries another finger 200 of sufficient vertical extent to engage all of the levers 110. By rocking of shaft 198 in a counterclockwise direction, all of the levers of both sets may be rocked clockwise as viewed in plan to prevent engagement of lever ends 186 with the wrap finger butts and of slides 120 with the butts 90 of lower sliders. Thus, despite timing up movements of the trick wheels, selective actions on the wrap fingers and sliders may be prevented. Movements of the shaft 198 are effected through a guided wire 202 connected to the upper end of a plunger 204, which extends downwardly to be acted upon by suitable cams on the main cam drum of the machine.

In order to impart to the embroidery yarns a sufficient extent of movement relative to the needles to cause them to be engaged by a plurality of needles, there is provided an abutment to effect retarding of the embroidery yarns relative to the needles in the general fashion described in the patent to Taggart 2,025,913, dated December 31, 1935. In the present machine, the abutment 208 for retarding the embroidery yarns takes the form of a finger 210, which is provided with a slight undercut indicated at 211 in Figures 17, 19 and 20, to prevent release of the yarn therefrom prior to completion of the wrapping. The abutment finger 210 is pivoted at 212 to the frame of the machine and is provided with an upright pin 214 passing through a slot in an arm 216 secured to an upright rod 218 journaled in the frame of the machine and capable of vertical movements against the action of spring 222, which reacts between the machine frame and a collar 224 on rod 218. Its downward movements are limited by a collar 226. To the upper end of the rod 218 is secured a bell crank provided with one arm 228 carrying a follower pin 230 engageable by cams

230, corresponding in number to the panels at which wrapping may take place. The other arm of the bell crank is provided with a vertical face 238 below which is a sloping face 240, these faces being adapted to be selectively engaged with a stop screw 234 under the action of spring 232, which tends to rotate the rod 218 clockwise as viewed in plan. The stop screw 234 is carried by a bracket 236, to which there is pivoted a lever 242 bifurcated to extend beneath the collar 224 and connected by means of a wire 244 to the upper end of a plunger 246 adapted to be acted upon by cams 248 on the main cam drum of the machine.

Figure 14 illustrates the abutment in the position it occupies during wrapping. As will be pointed out hereafter, to secure proper wrapping, slight inward movements are imparted to the abutment finger 210 momentarily in each wrapping operation. The cams 230 effect this action by causing the rod 218 to move slightly counter-clockwise, with the result that the action of arm 216 on pin 214 moves the wrap finger slightly inwardly.

During periods when wrapping is not to take place, for example, during heel and toe knitting, it is desirable to move the abutment away from the needles. This is effected by causing the plunger 246 to rise under the action of a cam 248, thereby raising, through lever 242, the rod 218. When this occurs, the sloping surface 240, rather than the vertical surface 238, is brought to the level of the stop screw 234, and a clockwise movement of the rod occurs under the action of spring 232 to move finger 210 away from the needles. At the same time, the cam follower pin 228 is raised above the level of the cams 230 so as not to be engaged thereby.

In Figure 15 there is illustrated the cam layout of the machine. Reference will not be made thereto in detail, in view of the fact that with a few exceptions the cams are entirely conventional, as will be apparent from consideration of the patents and application referred to above. It will be sufficient to point out that the machine may be of the two-feed variety having lower main feed cams at 250, upper main feed cams at 254, lower auxiliary feed cams at 252 and upper auxiliary feed cams at 256. During wrapping, knitting takes place at the main feed only.

A lower transfer cam is provided at 258 and an upper transfer cam is provided at 260. As is usual, the transfer butts of the lower and upper sliders are of different lengths, so that selective transfers of the needles may be accomplished. The knitting butts are, of course, also of different lengths to provide for segregation of the sole and instep needles.

A cam 262, arranged to act upon the knitting butts of the lower sliders, is arranged to bring the needles engaged by the lower sliders to a level to be wrapped. From this level, the slides 120, controlled by the patterning mechanism heretofore described, lower the sliders which engage needles which are not to be wrapped to a still lower level. After completion of the wrapping, a cam 264, engaging knitting butts, then raises all of the needles in the lower cylinder to a common level for passage together through the knitting wave. A cam 266, located just in advance of the wrapping position, serves to raise all of the upper sliders to a level above the position of the ends of the wrap fingers so as not to interfere therewith.

In order to render clearer the operations in-

volved in control of the needles, there is illustrated in diagrammatic fashion in Figure 16 the paths taken by the various butts of the lower sliders in the vicinity of the wrapping position. Let it be assumed, for example, that the narrow ribs are formed on three needles in the upper cylinder and the wide ribs on seven frame needles in the lower cylinder. During the wrapping operation, the lower sliders corresponding to the three narrow rib needles engage no needles and need be provided with no butts 90. The knitting butts of these idle sliders are indicated at A. The knitting butts of the seven sliders which engage needles in the panel under consideration are indicated in groups at B, C and C'. The knitting butts of a preceding panel are indicated at D.

The slides are indicated at 120 and are numbered 1 to 6, inclusive. The butts 90 which correspond to these sliders are also numbered 1 to 6, inclusive. Let it be assumed that during the formation of the particular course illustrated the sliders in the 1, 3, 4 and 5 positions are located inward so as to engage butts 90, while those in positions 2 and 6 are in outer position so as to miss the butts. In such case, if the various sliders are provided with the array of butts illustrated, it will be evident that the knitting butts of the sliders will take the position illustrated at B, C and C', with the result that only the needles corresponding to B will be raised in position to be wrapped, while those corresponding to C and C' will be depressed below the wrapping position. Attention may be called to the fact that the sliders in the 5 and 6 positions may be used to control the actions in entire panels. All of the sliders in the panel D, for example, contain butts in the 5 position, and by reason of the fact that the slider in the 5 position is in action, all of the needles corresponding to this panel D would have been depressed so as not to take yarn despite any swing of the wrap fingers corresponding to that panel.

It will thus be evident that the slides 120 effect the selective control of the lower sliders permitting to be wrapped those which do not have their butts engaged by the slides, and that by the proper position of butts entire panels of needles may be prevented from being wrapped. The particular yarns used in the wrapping are controlled by the action of the upper trick wheel and its connections to the wrap fingers.

Selective operation of the cams 262 and 264 is necessary and for this purpose there is used the mechanism illustrated in Figure 13. These cams 55 are mounted on plungers normally spring urged outwardly, and which are moved inwardly by engagement by adjustable screws 266 and 268 carried by a lever 270, pivoted at 272 and provided with an arm 274 engageable by a cam following lever 276 having an end 278 acted upon by cams 280 on the main cam drum. The cams 262 and 264 are desirably in operation only when wrapping is taking place.

The sequence of events occurring in the feeding of a wrap or embroidery yarn to the needles is illustrated in the distorted perspective views in Figures 17, 18, 19 and 20. The selection of the needles is, as has been described in connection with Figure 16, i. e., wrapping is to occur on the third and fifth needles of the seven needle panel of frame needles. Figure 17 shows these needles as they approach and pass slides 120 to effect their selective differentiation. The wrap finger 48 in Figure 17 is still inside the verge, and the 70 yarn extends therefrom to the last loop in which

it was knit in the preceding course. Figure 18 illustrates the position of the parts just after the wrap finger has been swung outwardly to cause its yarn to engage the depression in the abutment finger 210. The abutment finger will have restrained the yarn so that it is now partially wrapped about the first of the two needles B to knit it. Figure 19 shows a further development, this view embodying a line of vision somewhat to the right of Figure 18, i. e., the position of the abutment actually remains stationary between Figures 18 and 19. The wrap yarn is now fully engaged by the first of the needles and extends within the hook thereof and is about to be engaged by the second. At this time, it will be noted that the first rib needle following the frame panel is approaching the position of the abutment 210 so that the wrapping must be completed and the yarn withdrawn from the abutment. To insure proper wrapping of the last needle of the panel which is to be wrapped, and to avoid a premature slipping of the yarn off the abutment, the abutment is now given a slight inward movement by the action of the cam 230, thus insuring engagement of the yarn with the last needle to be wrapped. The abutment is then immediately withdrawn to its normal position by the release of pin 228 by cam 230 and the wrap finger is also withdrawn with the result that the wrap yarn slips off the abutment, this action being aided by reason of the curved path of the wrap finger. Thus the wrapping is completed before any interference with the wrap yarn can occur occasioned by the approaching rib needles.

If two or more fingers are located so as to wrap the same panel of needles, having their ends turned to approximately the same radial plane, selection of these fingers makes it possible to produce designs embodying more than one color or type of wrap yarn. It will be evident that the yarns passing through the loops to the idle fingers will not be engaged by the abutment, and consequently there will be no interference between the wrappings by the several yarns.

In a machine of this type, it is quite difficult to secure wrapping of the initial and final needles of the panel. With the use of the abutment operated as described, substantial numbers of needles may be wrapped in such a panel. The timing of the operations must, of course, be closely adjusted.

It will be evident that various rib arrangements may be wrapped. The ribs formed by the needles in the upper cylinder may be one or more wales in width. Those in the lower cylinder are, of course, preferably fairly wide to secure desirable designs.

By the use of the controlling device illustrated in Figures 4 and 5, it is unnecessary to have wasteful movements of the trick wheels occur. By the action of the lugs 172 on the chain 173, which preferably advances one-half link at the formation of every course, the guard 130 may be moved into position to cause interruptions in the advances of the trick wheels. Thus, for example, a particular wrapping arrangement may be maintained through a considerable series of courses to produce a panel of uniform width or design. The cams 168 operate independently to produce interruptions, for example, through the formation of a heel if patterning is to be continued in the instep following completion of the heel. The timing up position of the guard 134 is also controlled by one of the cams 168 having a lesser height.

It will be evident that adjacent wide ribs

formed by the lower cylinder needles may be wrapped in such fashion as to give in the finished stocking an impression of a wide panel of decoration. In fact, except for a possible area of no wrapping in the rear of the stocking, wrapping may be accomplished on all or substantially all of the broad ribs.

What I claim and desire to protect by Letters Patent is:

10. 1. A circular knitting machine of the superposed cylinder type comprising upper lower cylinders arranged to rotate in unison, needles adapted to slide in said cylinders, said needles being arranged during at least a part of the cycle of operation of the machine in panels in the upper and lower cylinders, respectively, to produce a broad ribbed fabric, sliders in the upper cylinder arranged to operate needles therein, means for controlling movements of needles in both cylinders to form stitches, means for projecting a wrap yarn outwardly between the cylinders and across the needle circle between panels of rib needles in the upper cylinder to present said yarn to at least one needle of a plain panel in the lower cylinder, and means for raising said sliders at the wrapping zone to avoid engagement of the wrap yarn therewith.
15. 2. A circular knitting machine of the superposed cylinder type comprising upper and lower cylinders arranged to rotate in unison, needles adapted to slide in said cylinders, said needles being arranged during at least a part of the cycle of operation of the machine in panels in the upper and lower cylinders, respectively, to produce a broad ribbed fabric, means for controlling movements of needles in both cylinders to form stitches, means for projecting a wrap yarn outwardly between the cylinders and across the needle circle between panels of rib needles in the upper cylinder to present said yarn to at least one needle of a plain panel in the lower cylinder, and means for raising said sliders at the wrapping zone to avoid engagement of the wrap yarn therewith.
20. 3. A circular knitting machine comprising a needle cylinder, needles adapted to slide in said cylinder, means for controlling movements of needles to form stitches, means for projecting a wrap yarn outwardly across the needle circle, and means for retarding said projected yarn movement with the cylinder to effect its engagement by at least one needle, said retarding means comprising a member normally located adjacent the needle circle during wrapping and means for moving said member inwardly momentarily as the last needle to be wrapped by a yarn engaged thereby passes its location, thereby to insure wrapping of said last needle.
25. 4. A circular knitting machine comprising a needle cylinder, needles adapted to slide in said cylinder, means for controlling movements of needles to form stitches, means for presenting a wrap yarn to said needles, and means for selectively locating said needles to take said wrap yarn, said wrap yarn presenting means comprising a carrier having axially extending slots therein, and a plurality of wrap yarn carrying fingers located in said slots in spaced relationship but having their wrap yarn carrying ends located closely adjacent each other so as to move in substantially the same yarn presenting path.
30. 5. A circular knitting machine of the superposed cylinder type comprising upper and lower cylinders, double ended needles adapted to slide in said cylinders, means for selecting needles in said lower cylinder, wrap thread feeding means

movably mounted within said upper cylinder, means for moving said wrap thread feeding means across the lower needle circle, and means for cooperating with said wrap thread feeding means when so moved to cause a wrap thread to be presented to at least two selected needles in said lower cylinder during the same course of knitting.

6. A circular knitting machine of the superposed cylinder type comprising coaxial cylinders, double ended needles adapted to slide in said cylinders, means for selecting needles in one of said cylinders, wrap thread feeding means, means for moving said wrap thread feeding means across the needle circle, and means for cooperating with said wrap thread feeding means when so moved to cause a wrap thread to be presented to at least two selected needles during the same course of knitting.

7. A circular knitting machine of the superposed cylinder type comprising coaxial cylinders, needles adapted to slide in said cylinders, means for arranging adjacent groups of needles in the cylinders for the production of broad ribbed fabric, wrap thread feeding means, means for moving said wrap thread feeding means across the needle circle, and means for cooperating with said wrap thread feeding means when so moved to cause a wrap thread to be presented to at least two selected needles during the same course of knitting.

8. A circular knitting machine of the superposed cylinder type comprising coaxial cylinders, needles adapted to slide in said cylinders, means for transferring needles between the cylinders, wrap thread feeding means, means for moving said wrap thread feeding means across the needle circle, and means for cooperating with said wrap thread feeding means when so moved to cause a wrap thread to be presented to at least two needles during the same course of knitting.

9. A circular knitting machine of the superposed cylinder type comprising coaxial cylinders, needles adapted to slide in said cylinders, said needles being arranged during at least a part of the cycle of operation of the machine in both cylinders to produce reversely concatenated loops, and means for effecting movement of a wrap yarn outwardly, between the cylinders, across the needle circle, circumferentially through an angle substantially exceeding that between adjacent needles, and between needles in one cylinder to present the yarn to at least one needle in the other cylinder.

10. A circular knitting machine of the superposed cylinder type comprising coaxial cylinders, needles adapted to slide in said cylinders, said needles being arranged during at least a part of the cycle of operation of the machine in both cylinders to produce reversely concatenated loops, means for effecting movement of a wrap yarn outwardly between the cylinders, across the needle circle, and between needles in one cylinder to present the yarn to one or more needles in the other cylinder, and means for selectively locating needles in the last mentioned cylinder to take said wrap yarn.

11. A circular knitting machine of the superposed cylinder type comprising coaxial cylinders, needles adapted to slide in said cylinders, said needles being arranged during at least a part of the cycle of operation of the machine in both cylinders to produce reversely concatenated loops, means for effecting movement of a wrap yarn outwardly between the cylinders and across the

needle circle between needles in one cylinder, and means for retarding said projected yarn from movement with the cylinders to effect its engagement by at least one needle in the other cylinder.

5 12. A circular knitting machine of the superposed cylinder type comprising coaxial cylinders, needles adapted to slide in said cylinders, said needles being arranged during at least a part of the cycle of operation of the machine in both cylinders to produce reversely concatenated loops, means for effecting movement of a wrap yarn outwardly between the cylinders and across the needle circle between needles in one cylinder, and means for retarding said projected yarn from movement with the cylinders to effect its engagement by at least one needle in the other cylinder, said retarding means comprising a member movable outwardly to an inoperative position when wrapping is not occurring.

10 13. A circular knitting machine of the superposed cylinder type comprising coaxial cylinders, needles adapted to slide in said cylinders, said needles being arranged during at least a part of the cycle of operation of the machine in both cylinders to produce reversely concatenated loops, means for effecting movement of a wrap yarn outwardly between the cylinders and across the needle circle between needles in one cylinder, and means for retarding said projected yarn from movement with the cylinders to effect its engagement by at least one needle in the other cylinder, said means for effecting outward movement of a wrap yarn rotating with the cylinders and closely trailing a panel of needles in the first mentioned cylinder.

15 14. A circular knitting machine of the superposed cylinder type comprising coaxial cylinders, needles adapted to slide in said cylinders, said needles being arranged during at least a part of the cycle of operation of the machine in both cylinders to produce reversely concatenated loops, means for effecting movement of a wrap yarn outwardly between the cylinders and across the needle circle between needles in one cylinder, and means for retarding said projected yarn from movement with the cylinders to effect its engagement by at least one needle in the other cylinder and for releasing said projected yarn for movement with the cylinders before it is reached by any needle in the first mentioned cylinder, said means for effecting outward movement of a wrap yarn rotating with the cylinders and closely trailing a panel of needles in the first mentioned cylinder.

20 15. A circular knitting machine of the superposed cylinder type comprising coaxial cylinders, needles adapted to slide in said cylinders, a plurality of means, each for presenting a wrap yarn to a plurality of needles in a single course of knitting, means for selectively causing the last named means to present their yarns to needles, and means for selectively locating needles in position to take said wrap yarns.

25 16. A circular knitting machine of the superposed cylinder type comprising coaxial cylinders, needles adapted to slide in said cylinders, a plurality of wrap fingers carrying wrap yarns and mounted to project their wrap yarns in substantially the same radial path with respect to said cylinders, and means for selectively causing each of the wrap fingers to present its yarn to a plurality of needles.

30 17. A circular knitting machine of the superposed cylinder type comprising coaxial cylinders, needles adapted to slide in said cylinders, means

for presenting a wrap yarn to at least one needle in one of the cylinders, sliders in the other cylinder arranged to operate needles therein, and means for moving sliders at the wrapping zone to avoid engagement of the wrap yarn therewith.

18. A circular knitting machine of the superposed cylinder type comprising coaxial cylinders, needles adapted to slide in said cylinders, means for presenting a wrap yarn to at least one needle in one of the cylinders, elements carried by the other cylinder, and cam means for moving said elements at the wrapping zone from positions in which, if maintained, they might engage wrap yarn, to other positions to avoid engagement of the wrap yarn therewith during wrapping.

19. A circular knitting machine of the superposed cylinder type comprising coaxial cylinders, needles adapted to slide in said cylinders, a wrap thread feeding finger, means for actuating said finger to effect wrapping, and a member movable axially with respect to the cylinders for supporting said finger, so that the finger may be located within the upper cylinder in its active position or above said cylinder where it may be conveniently threaded or replaced.

20. A circular knitting machine of the superposed cylinder type comprising coaxial cylinders, needles adapted to slide in said cylinders, means for presenting a wrap yarn to at least one needle in one of the cylinders, sliders in the other cylinder arranged to operate needles therein, means for moving sliders to effect transfer of needles between the cylinders, and means for moving sliders at the wrapping zone to avoid engagement of the wrap yarn therewith.

21. A circular knitting machine comprising, in combination, a needle cylinder, a second needle cylinder axially opposed to the first mentioned cylinder, double ended needles in said cylinders, a carrier arranged concentrically with respect to said cylinders, independent thread guides in said carrier each adapted to supply a design thread and to serve a group of at least two of the needles, said guides extending in an axial direction with respect to the needle cylinders and being in the form of blade-like elements each provided with a thread guiding portion which extends at an angle to the blade, means for moving said guides radially with respect to the needle circle suchwise as to carry their threads across said circle, means constructed and arranged to lap each of said design threads about at least two needles, cam means for effecting lengthwise movement of the needles, and means for moving said needles selectively so that in any of the aforesaid groups of needles, any one of the group can be caused to knit the design thread supplied by the appropriate guide while others of said group do not.

22. A circular knitting machine of the superposed cylinder type comprising coaxial rotary cylinders, needles adapted to slide in said cylinders, a plurality of means, each for presenting a wrap yarn to a plurality of needles in a single course of knitting, means for selectively causing the last last named means to present their yarns to needles, and means for selectively locating needles in position to take said wrap yarns.

23. A circular knitting machine of the superposed cylinder type comprising coaxial cylinders, needles mounted in said cylinders, means for transferring needles from one cylinder to the other during a knitting operation, means for causing transferred needles to draw yarn to form stitches, means for selecting needles to be

wrapped, and means for effecting wrapping of a plurality of selected needles by a wrap yarn in a single course, said means for selecting needles and for effecting wrapping being located between the transferring means and the means for causing needles to draw yarn.

24. A circular knitting machine comprising, in combination, a needle cylinder, a second needle cylinder axially opposed to the first mentioned cylinder, double-ended needles in said cylinders, a carrier arranged concentrically with respect to said cylinders, independent thread guides in said carrier each adapted to supply a design thread and to serve a group of at least two of the needles, said guides extending in an axial direction with respect to the needle cylinders and each being provided with a thread guiding portion which extends at an angle to the main portion thereof, means for moving said guides radially with respect to the needle circle suchwise as to carry their threads across said circle, means constructed and arranged to lap each of said design threads about at least two needles, cam means for effecting lengthwise movement of the needles, and means for moving said needles selectively so that in any of the aforesaid groups of needles, any one of the group can be caused to knit the design thread supplied by the appropriate guide while others of said group do not.

30 25. A circular knitting machine of the superposed cylinder type comprising upper and lower cylinders arranged to rotate in unison, needles adapted to slide in said cylinders, said needles being arranged during at least a part of the cycle of operation of the machine in multiple needle panels in the lower cylinder flanked by needles in the upper cylinder to produce a ribbed fabric, means for controlling movements of needles in both cylinders to form stitches, and means including a radially movable wrap yarn guide, constructed and arranged to present a wrap yarn to substantially all of the needles in a lower cylinder panel without exerting damaging forces on the flanking needles in the upper cylinder.

45 26. A circular knitting machine of the superposed cylinder type comprising coaxial cylinders, needles adapted to slide in said cylinders, means for presenting a wrap yarn to at least one needle in one of the cylinders, elements carried by the other cylinder, and means for moving said elements at the wrapping zone from positions in which, if maintained, they might interfere with wrapping, to other positions to avoid interference with wrapping.

55 27. A circular knitting machine of the superposed cylinder type comprising coaxial cylinders, double ended needles adapted to slide in said cylinders, means for selecting needles in one of said cylinders, main and auxiliary knitting stations, 60 wrap thread feeding means, means for moving said wrap thread feeding means across the needle circle, and means for cooperating with said wrap thread feeding means when so moved to cause a wrap thread to be presented to at least two selected needles during the same course of knitting.

28. A circular knitting machine of the superposed cylinder type comprising coaxial cylinders, needles adapted to slide in said cylinders, means 70 for transferring needles between the cylinders, verge bits arranged to cooperate with needles knitting in one of the cylinders, wrap thread feeding means, means for moving said wrap thread feeding means across the needle circle, and means for cooperating with said wrap thread feeding

means when so moved to cause a wrap thread to be presented to at least two needles during the same course of knitting.

29. A circular knitting machine of the superposed cylinder type comprising coaxial cylinders, needles adapted to slide in said cylinders, means for transferring needles between the cylinders, wrap thread feeding means including a wrap finger, means for positively moving said wrap fin-

ger both outwardly to carry the wrap thread across the needle circle and inwardly to return the wrap thread to an inactive position, and means for cooperating with said wrap thread feeding means when the wrap thread is moved across the needle circle to cause the wrap thread to be presented to at least two needles during the same course of knitting.

JAMES L. GETAZ.
